DECORATIVE PANEL FOR CIGARETTE LIGHTER
OR THE LIKE

Jerome Hammer, New York, N.Y., assignor to Panation
Trade Company, New York, N.Y.

Application January 13, 1958, Serial No. 49,210

Term of patent 14 years

(Cl. D48—27)

Fig. 1

Fig. 2

Fig. 1 is a view in side elevation of a decorative panel for cigarette lighters showing my new design, the broken lines being for illustrative purposes only.

Fig. 2 is an enlarged sectional view thereof taken on line 2—2 of Fig. 1.

I claim:

The ornamental design for a decorative panel for cigarette lighter or the like, as shown and described.
